UNITED STATES PATENT OFFICE.

CIRTHBERT C. MUNROE, OF BOSTON, MASSACHUSETTS.

THILL-COUPING.

SPECIFICATION forming part of Letters Patent No. 405,108, dated June 11, 1889.

Application filed March 30, 1889. Serial No. 305,383. (No model.)

To all whom it may concern:

Be it known that I, CIRTHBERT C. MUNROE, a citizen of Canada, and a resident of Boston, in the county of Suffolk and State of Massachusetts, have invented new and useful Improvements in Thill-Couplings, of which the following, taken in connection with the accompanying drawings, is a specification.

This invention relates to improvements in thill-couplings; and it is carried out as follows, reference being had to the accompanying drawings, wherein—

Figure 1 represents a plan view of the invention. Fig. 2 represents a longitudinal section on the line X X shown in Fig. 1. Fig. 3 represents a detail plan view of the shaft-iron, and Fig. 4 represents a cross-section on the line Y Y shown in Fig. 2.

Similar letters refer to similar parts whenever they occur on the different parts of the drawings.

a represents the carriage-axle, as usual, to which is secured the clasp b, having the downwardly-projecting screws b' b'', passing through perforations in the yoke c and provided with nuts b'' b'', by means of which the axle, clasp, and yoke are firmly secured together.

d represents the shaft-iron, having a forked end d', to which is secured, or made in one piece with, the ball d'', as shown in detail in Fig. 3.

d' d'' are cylindrical journals or trunnions connecting the said ball d'' with the forked end d' of the shaft-iron d, as shown in said Fig. 3.

In one piece with the yoke c is made the ball-bearing c', adapted to receive the ball d'' of the shaft-iron, and e is a detachable ball-bearing cap adapted to fit against the rear portion of the said shaft-iron ball d'', as shown. Said cap may be made of hard rubber, metal, or other suitable material, without departing from the essence of my invention.

c'' c'' are guide-ribs on the yoke c, between which the under side of the cap-piece e is

guided, as shown in Fig. 4. The cap e is secured to the yoke c by means of the screw-bolt f, passing loosely through a perforation in the cap e and screwed through the yoke, which at this place is preferably made of increased thickness, as shown in Figs. 2 and 4. f' is a check-nut on the lower projecting end of the screw-bolt f for the purpose of preventing said bolt from working loose. 55

The screw-bolt f is arranged inclined to the yoke c, as shown in Fig. 2, so as to cause the cap e to be forced against the rear portion of the shaft-iron ball d'' with a proper frictional resistance, and thus preventing the coupling 60 from rattling while in use.

By adjusting the position of the inclined screw f the wear on the ball and ball-joint may be taken up from time to time as may be needed to prevent rattling and to obtain the necessary frictional resistance between the ball and its ball-bearing. 65

The invention is very simple in construction, is composed of very few parts, and by its use a proper connection is established between the shaft-iron and the axle and all rattling and consequent unnecessary wear of the jointed parts prevented. 70

Having thus fully described the nature, construction, and operation of my invention, I 75 wish to secure by Letters Patent, and claim—

The herein-described thill-coupling, consisting of the yoke c, secured to the carriage-axle and having the ball-bearing c' and guide-ribs c'' c'', as described, combined with the adjustable cap e, the inclined fastening-bolt f, and the forked shaft-iron having the ball d'', substantially as and for the purpose set forth. 80

In testimony whereof I have signed my name 85 to this specification, in the presence of two subscribing witnesses, on this 11th day of February, A. D. 1889.

CIRTHBERT C. MUNROE.
